Primary Examiner — Paula Allen Greene(74) *Attorney, Agent, or Firm* — Banner & Witcoff, Ltd.(57) **CLAIM**

The ornamental design for a wireless bodypack, as shown and described.

DESCRIPTION

FIG. 1 is a top, front, right perspective view of a wireless bodypack showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines immediately adjacent to the shaded area define the bounds of the claimed design and form no part thereof. The broken lines depicting the remainder of the wireless bodypack show features that form no part of the claimed design.

1 Claim, 5 Drawing Sheets(56)
